[57] CLAIM

The ornamental design for a garment straps retainer, as shown and described.

DESCRIPTION

FIG. 1 is a perspective view of a garment straps retainer, showing my new design;

FIG. 2 is a top plan view of the garment straps retainer of FIG. 1;

FIG. 3 is a bottom plan view of the garment straps retainer of FIG. 1;

FIG. 4 is a front elevational view of the garment straps retainer of FIG. 1, the rear elevational view being a mirror image thereof; and,

FIG. 5 is a right side elevational view of the garment straps retainer of FIG. 1, the left end elevational view being a mirror image thereof.

FIG. 1

FIG. 2

FIG. 3

FIG. 4

FIG. 5
